AUTOMATIC CUT-OFF DEVICE

Roscoe D. Conklin, Rahway, N. J., assignor to
National Pneumatic Company, New York, N. Y.,
a corporation of West Virginia

Application July 14, 1933, Serial No. 680,344

4 Claims. (Cl. 226—127)

This invention relates to improvements in the combination with a liquid supply or discharge pipe, of means for automatically cutting off the flow of liquid therethrough.

5 The invention is particularly adapted for use in combination with liquid fuel supply nozzles such as are employed in conjunction with gasoline pumps and the like.

10 Such devices are provided with a trigger or lever actuated valve for moving it to open position and a spring for returning it to closed position.

15 An object of this invention is to provide automatically operating apparatus controlled by the liquid fuel level for releasing the main valve so that its spring may close it when the container into which the fuel is being discharged, is filled.

20 These and many other objects as will appear from the following disclosure, are secured by means of this invention.

This invention resides substantially in the combination, construction, arrangement and relative location of parts, all as will appear more fully in the following specification:

25 Referring to the drawing:

Figure 1 is a top plan view of the complete device of this invention;

Fig. 2 is a side elevational view thereof;

Fig. 3 is a vertical, central, cross sectional view 30 through the end of the vacuum pipe;

Fig. 4 is a vertical, central, cross sectional view through the valve in the vacuum pipe;

Fig. 5 is a similar view taken at right angles to the view of Fig. 4.

35 In the discharge of liquid from a pipe or nozzle into a container, it is often difficult to ascertain when the container is full so that the fuel supply may be cut off without the loss of liquid by over-flowing. This difficulty is ever present in filling 40 gasoline tanks on automobiles. When it is desired to fill the tank full of gasoline, unless the operation is carefully supervised, the tendency to fill the tank to over-flowing with a consequent loss of gasoline, is always present.

45 The prime object of this invention is to provide automatically acting apparatus controlled by the liquid level of the liquid in the container for shutting off the supply of liquid thereto when the container is substantially full. The details 50 of construction of the apparatus by means of which these objects are obtained, is clearly illustrated in the drawing and will now be described in detail in connection therewith.

In Figs. 1 and 2 a gasoline discharge nozzle 1 55 is shown by way of illustration. This nozzle is provided with a fitting 2 which has therein, a valve 3 having a valve stem 4 extending exteriorly thereof. As shown in Fig. 5 the inner end of the valve stem 4 is provided with a seat 4' 60 for cutting off the flow of gasoline and a spring

4" is positioned to normally urge the valve to closed position and hold it seated. At 5, is a trigger or lever, pivotally mounted on the fitting 2 and engaging the valve stem 4 by means of which the valve may be unseated against the action of the spring 4". Pivotally mounted on the fitting at 7, is a bell crank lever having the arms 8 and 11. Arm 8 is provided at its lower end 9 with a series of teeth or serrations positioned to be engaged by a suitably shaped nose 10 on the end of lever 5. The lever 11 is operatively connected by a stud 12 to a diaphragm 13 within the casing 14, mounted on the nozzle structure. Interposed between the casing 14 and the upper face of diaphragm 13, is a spring 14' which normally holds the diaphragm and the bell crank lever in the position shown in Fig. 2.

5 The casing 14 is connected by a branch pipe 15 to a key fitting 16 from which extends in one direction and lying parallel to the nozzle, a small pipe 17. This pipe terminates adjacent the discharge end of the nozzle 1 as is clearly apparent in Fig. 2. At this point it may be noted that the pipe 17 may extend inside of the nozzle, if desired, but a simpler construction results by mounting it adjacent the exterior of the nozzle as shown in Figs. 1 and 2. The lower end of pipe 17 is provided with a coupling member 24 to which is secured a small casing 25 having a number of ports as shown and enclosing a small cork or similar ball 26. When the nozzle is in a vertical position, the cork ball 26 falls back to close the end of the fitting 24. Interposed in the pipe 17, adjacent valve 3 is a ball valve arrangement 25 illustrated in Figures 4 and 5. The pipe 17 is provided with a fitting 23 forming a casing having a port 29 and providing a space for a steel ball 50. The casing is internally constructed to provide two seats as shown so that the ball in the position shown in Figure 4, seals the left hand portion of pipe 17. Fitting 23 is provided with an extension to which a tubular casing 30 is attached. Mounted in the casing is a plunger 31 which extends into the chamber of fitting 23 and engages the steel ball 50. A spring 32 is interposed between the plunger 31 and a second plunger 33, extending through the lower wall of casing 30. This plunger 33 is connected to or is in a position to be engaged by an arm 28, mounted on the valve stem 4. When the nozzle is in a vertical position, ball 26 seals pipe 17 at the lower end and steel ball 50 seals the pipe intermediate its ends. When the nozzle is moved down into the tank opening, ball 26 falls to the lower end of casing 25.

55 The other end of fitting 16 is connected by pipe 18 to a small tank 19 so as to discharge thereinto. A similar pipe 20 extends from this tank to the suction port of any suitable form of vacuum pump 21 which is provided with a driving 60

pulley 22. The pump may be driven from any suitable power source, which, when the invention is applied to an ordinary pump or nozzle, may be the electric motor which drives the gasoline 5 pump. As is well known in this art, such pumps are usually provided with a hook upon which the nozzle and hose is mounted when not in use. This hook controls a switch in the motor circuit which is closed when the nozzle and hose is removed from the hook. Thus with this invention 10 the vacuum pump will start in operation when the nozzle is removed from the hook starting the gasoline pump motor. Tank 19 is provided with a small drain cock 22. The nozzle fitting 2 is of course, connected to the usual supply pipe 6 which, in the case of a gasoline pump, is usually a flexible rubber or metal tube connected to the gasoline pump. The tank 19 may be mounted directly on the nozzle or hose, or may 15 be mounted in the gasoline pump casing and pipe 18 may then be a flexible rubber, or metal tube. The bell crank lever 11-8, is provided with a finger operated bolt extension 7.

In the operation of this device, the nozzle is 20 removed from the hook with the result that the gasoline pump motor is set in operation and the vacuum pump 21 is likewise set in operation. The nozzle 1 is then placed in the filling opening of the tank. Lever 5 is then pulled upwardly opening valve 3. The nose 10 of lever 5 is retained in its lifted position by engagement with the notches on lever 9. When lever 5 is pulled upwardly to open valve 3, extension 28 causes the plunger 31 to force the steel ball 50 on to the 25 seat to close port 29. The spring 32 is provided in this connection to permit any necessary overtravel of the plunger 31 when the lever 5 is operated.

With the pump running, air is drawn through 30 the pipe 17, fitting 16, pipe 18, tank 19, pipe 20, pump casing 21, and discharged to the atmosphere. When the liquid level rises in the tank it enters casing 25 and causes the light cork or similar ball 26 to float upwardly and to finally seal 35 the end of pipe 17 just as the tank is full. The result is that the air is then directly drawn from casing 14. Atmospheric pressure operating on the under surface of the diaphragm pushes it upwardly, at the same time operating the bell 40 crank lever to release lever 5. Spring 4" in valve 3, is therefore free to seat the valve 4' and moves the lever 5 back in position as shown in Fig. 2. The closing of valve 3 of course shuts off the supply of gasoline or liquid to the tank and prevents 45 the tank from overflowing. At the same time as valve 3 closes, plunger 31 drops back and frees steel ball 50. Since the vacuum pump is still running, air will be drawn through port 28 in fitting 23 and into pipe 17. When the nozzle is 50 moved to a vertical position the steel ball will fall back to the position shown in Figure 4, sealing pipe 27. With this arrangement it will be seen that little or no gasoline or other liquid can get into pipe 17, the double ball arrangement 55 which prevents this, not interfering with the operation of the device. The nozzle is then lifted to vertical position and replaced on the hook. This stops the pump 21 and diaphragm 13 moves back to normal position under the action of 60 spring 14'. Any liquid trapped in tank 19 may be drained therefrom through the cock 22, from time to time. The extension 7' of the bell crank lever is provided for the purpose of manually releasing 65 lever 5 at any time.

While both the tank 19 and the double valve arrangement are shown to prevent any liquid reaching the pump, it is apparent that the tank 19 is not essential and need only be used as an extra safeguard against liquid reaching the pump. 5

From the above description it will be apparent that this invention resides in certain principles of construction and operation which may be embodied by those skilled in the art in other physical forms without departure from the scope of 10 this invention. I do not desire, therefore to be strictly limited to the disclosure as given for purpose of illustration, but rather to the scope of the appended claims.

What I seek to secure by United States Letters 15 Patent is:

1. A device as described, comprising a liquid discharge nozzle having a valve therein, a lever for unseating said valve, locking means for holding the lever in operating position, a fluid pressure motor connected to said locking lever, an air pipe terminating adjacent the discharge end of the nozzle, means for creating a vacuum in said pipe, a connection between said pipe and said motor, a ball check valve in said air pipe, and 20 means actuated by said lever for unseating said ball check valve when the lever is actuated. 25

2. A device as described, comprising a liquid discharge nozzle having a valve therein, a lever for unseating said valve, locking means for holding the lever in operating position, a fluid pressure motor connected to said locking lever, an air pipe terminating adjacent the discharge end of the nozzle, means for creating a vacuum in said pipe, a connection between said pipe and said motor, a ball check valve in said air pipe, means actuated by said lever for unseating said ball check valve when the lever is actuated, and a float valve 30 mounted in a casing at the end of said pipe. 35

3. A device as described comprising a liquid supply nozzle having a spring seated valve therein, a lever for unseating said valve, locking means for holding the lever in actuated position, a fluid pressure motor connected to said locking means, an air pipe terminating adjacent the discharge 45 end of the nozzle, means for creating a vacuum in said pipe, a connection between said pipe and said motor, a fitting in said air pipe forming a casing having an aperture open to the atmosphere and a ball check valve therein, said fitting having 50 a seat for the ball to seal a portion of said air pipe and a seat positioned so that the ball may seal said aperture and means operated by said lever for moving the ball to said second seat to close said aperture. 55

4. A device as described comprising a liquid supply nozzle having a spring seated valve therein, a lever for unseating said valve, locking means for holding the lever in actuated position, a fluid pressure motor connected to said locking means, an air pipe terminating adjacent the discharge end of the nozzle, means for creating a vacuum in said pipe, a connection between said pipe and said motor, a fitting in said air pipe forming a casing having an aperture open to the atmosphere, a ball check valve therein, said fitting having a seat for the ball to seal a portion of said air pipe, a seat positioned so that the ball may seal said aperture, means operated by said lever for moving the ball to said second seat to close 60 said aperture, and a float valve mounted in an apertured casing attached to the end of said air pipe. 65
